(57) **CLAIM**

The ornamental design for a moss pole, as shown and described.

DESCRIPTION

FIG. 1 is a top perspective view of a moss pole showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof; and,

FIG. 9 is a top perspective view of the moss pole shown in an alternative configuration.

The broken lines throughout the drawing figures depict portions of the moss pole that form no part of the claimed design.
